AQUARIUM SUPPORT BASE

Aaron E. Gandy, 2613 W. Storey,
Midland, Tex. 79701

Filed May 17, 1968, Ser. No. 11,993

Term of patent 14 years

Int. Cl. D30—01

U.S. Cl. D30—12

FIG. 1

FIG. 2

FIG. 3

FIGURE 1 is a perspective view of an aquarium support base showing my new design;

FIGURE 2 is a top plan view thereon; and

FIGURE 3 is an elevational view thereof.

The broken line representation of an aquarium in FIGURE 1 is for purposes of illustration only.

I claim:

The ornamental design for an aquarium support base, substantially as shown and described.
